UNITED STATES PATENT OFFICE

126,620

DESIGN FOR A BADGE OR LIKE ARTICLE

Robert Witt, Chicago, Ill., assignor to The American Legion, Department of Illinois, Chicago, Ill.

Application August 19, 1940, Serial No. 94,506

Term of patent 7 years

To all whom it may concern:

Be it known that I, Robert Witt, a citizen of the United States, residing at Chicago, in the county of Cook and State of Illinois, have invented a new, original, and ornamental Design for a Badge or Like Article, of which the following is a specification, reference being had to the accompanying drawing, forming part thereof.

In the drawing:

I claim:

The ornamental design for a badge or like article, substantially as shown.

ROBERT WITT.
